Attorney

UNITED STATES PATENT OFFICE.

MARSHALL H. PEACOCK, OF DETROIT, MICHIGAN, ASSIGNOR TO PEACOCK RADIATOR GUARD COMPANY, INC., OF DETROIT, MICHIGAN, A CORPORATION OF MICHIGAN.

RADIATOR GUARD.

Application filed March 5, 1920. Serial No. 363,461.

To all whom it may concern:

Be it known that I, MARSHALL H. PEACOCK, a citizen of the United States, and residing at Detroit, in the county of Wayne and State of Michigan, have invented a new and Improved Radiator Guard, of which the following is a specification.

This invention relates to means for protecting the fronts of the radiators of motor vehicles, particularly of passenger automobiles, and its object is to provide a guard which may be quickly and easily attached to and detached from the shell of the radiator as a unit without the necessity of changing the radiator shell in any manner or detaching any permanent part of the vehicle.

This invention consists in a series of upright guard bars, preferably of pressed steel, extending across the radiating surfaces and also extending part way over the shell or casings for the upper and lower tanks, of cross bars to which the guard members are secured, and means for holding the guard in position.

It further consists in the details of construction illustrated in the accompanying drawing and particularly pointed out in the claims.

In the drawing, Fig. 1 is a front elevation of a radiator provided with my improved guard. Figs. 2, 3 and 4 are sections on a larger scale on the lines 2—2, 3—3 and 4—4 respectively.

Similar reference characters refer to like parts throughout the several views.

The heat radiating members of the radiators commonly used on motor vehicles are usually made of very thin copper and are liable to be bent and broken by slight shocks or blows. To prevent such injury I have produced a guard which is pleasing in appearance and which can be readily attached to and detached from the shell or casing of the radiator.

This guard comprises a structure which consists in the flat cross bars 1 whose ends 2 are bent back to engage the sides 3 of the radiator shell or casing. These bars are preferably of somewhat resilient steel so that they will grip the radiator and prevent rattling. To these bars are secured the upright guard members 4 which are preferably stamped up from heavy sheet steel so as to

be of channel shape in cross section and are secured to the cross bars 1 by means of bolts 5. The ends of these guard members are preferably tapered and these members may be nickel plated to give them a pleasing appearance.

Secured to the cross bars, and preferably just back of the middle guard member, and preferably by the same bolts 5 which secure this central guard member to the cross bars 1, is a flat resilient retaining member 6 whose upper end 7 is adapted to be slipped up back of the top front plate 8 of the shell or casing of the radiator and whose lower portion 9 may be bent up around the bottom front plate 10 of this shell or casing. The spring of this retaining member holds the cross bars against the radiator casing. Any desired means may be employed to lock the guard in position on the radiator. I have shown a screw 11 which extends through the parts 9 and 10 and into a threaded hole in the up-turned end 12. When this screw is taken out, the guard may be slipped down as a unit and removed.

I prefer to use but one bolt to secure each guard member to each cross bar so that the parts may be swung on these bolts to bring the guard members against each other to collapse the structure for shipment as an assembled product.

As further securing means I may provide the device shown in Fig. 3, which consists in the screws 14 and the washers 15. When this guard is to be attached, the shell of the radiator is removed and the upper end 7 of the central bar 6 is slipped under the top part 8 of the shell. The washers 15 are now placed against the back of the side members 16 of the radiator shell and the screws 14 screwed into proper holes in the cross bars 1. After being tightened down the front ends of the screws may be riveted down.

If desired, when these screws and washers are used, the upper end 7 may be left on the outside of the top plate 8 of the shell. The distance between the ends of the guard members 4 and the shell may be varied as desired, but is preferably not more than that shown in the drawing. Or they may contact directly with the shell.

The proportions and sizes of the various parts may all be changed by those skilled in

the art without departing from the spirit of my invention as set forth in the following claims.

I claim:-

- 5 1. A guard for automobile radiators comprising a unitary structure adapted to be attached and detached as a whole from the radiator, and consisting of two flat cross bars of resilient metal having their ends bent back to grip the radiator to which the guard is attached, upright bars extending across the air passages in the radiator and bolted to the front sides of the cross bars, and means to secure the guard to the radiator.
- 10 10 2. A guard for automobile radiators comprising a unitary structure adapted to be at-
- 15

tached and detached as a whole from the radiator and consisting of two flat cross bars of resilient metal having their ends bent back to grip the radiator to which the guard is attached, upright bars extending across the air passages in the radiator and bolted to the front sides of the cross bars, and means to secure the guard to the radiator, said means consisting of an upright retaining bar secured to the rear side of the cross bars, the upper end of the retaining bar being adapted to be inserted back of the front top plate of the radiator casing and the lower end to be attached to the front bottom plate of the radiator casing.

MARSHALL H. PEACOCK.
